(CL. D26—1)

FIG. 1

FIG. 2

FIG. 3

FIG. 4

FIG. 5

FIG. 6

FIGURE 1 is a front elevation of a "duplex grounding outlet with contoured faces" in accordance with the new design;

FIG. 2 is a fragmentary cross sectional view taken on line 2-2 of FIGURE 1;

FIG. 3 is a cross sectional view taken on line 3-3 of FIGURE 1;

FIG. 4 is a cross sectional view taken on line 4-4 of FIGURE 1, the bottom being broken away for convenience of illustration;

FIG. 5 is a cross sectional view taken on line 5-5 of FIGURE 1, the bottom being broken away for convenience of illustration; and

FIG. 6 is an end elevational view, the bottom being broken away for convenience of illustration.

The essential features of the design invention reside in the solid line depictions.

This application is a continuation-in-part of my design application Serial No. D.-67,133, filed October 18, 1961.

I claim:

The ornamental design for "duplex grounding outlet with contoured faces," substantially as shown and described.
